United States Patent Office.

RALPH HUNT, OF MILFORD, NEW JERSEY, ASSIGNOR TO DANIEL M SPROGLE, OF ANNAPOLIS, MARYLAND.

Letters Patent No. 104,737, dated June 28, 1870.

IMPROVEMENT IN BURIAL-CASES.

The Schedule referred to in these Letters Patent and making part of the same.

To all whom it may concern:

Be it known that RALPH HUNT, of Milford, Hunterdon county and State of New Jersey, has invented a new and improved Coffin or Burial-Case, Receptacle, or Box; and I do hereby declare that the following is a full, clear, and exact description thereof, which will enable others skilled in the art to make and use the same, reference being had to the accompanying drawing forming part of this specification.

The present invention relates to a novel and useful box or receptacle for coffins or other burial-cases, when deposited in the ground, the object being to provide such a receptacle or box therefor as will not decay or rot, and will also prevent the decay of the wood or other material of which the coffin, &c., contained or inserted in it, is made; and, for this purpose,

It consists in forming the said box or receptacle, or what I deem proper to term a "portable tomb," of the ordinary cement, molded either in sections or in parts, or with its body or main portion in one piece, and its top, lid, or cover in sections or in one piece, which body and top, after the coffin has been placed within the same, are cemented together in any proper manner.

In the accompanying drawing my improved coffin-box or receptacle is illustrated,

Figure 1 being a plan or top view of the same, with the cover or lid removed, and

Figure 2, a transverse vertical section, taken in the plane of the line z z , fig. 1.

Similar letters of reference indicate like parts.

A in the drawing represents the body-portion of my improved box or receptacle for a coffin or other burial-case, which body is provided with sides, B, and ends, C, and is made of a shape upon its inside corresponding to that of the outside of the coffin or burial-case which it is to hold or contain.

D, the top or lid for the body A, which lid is made of a suitable shape to entirely cover the box A, over the upper edges of the sides and ends of which it is set and fits, by its grooves, E, made of suitable shape therefor, and extending in the proper direction.

Both the body A and lid D are made of the ordinary and well-known cement, which, being mixed with water so as to reduce it to a pasty condition, is then molded into the proper and desired shape for the body and cover of the box, either with each in one piece, or in sections or parts cemented together, according as may be found most expedient for convenience in transportation and use.

By using cement, a box or receptacle is obtained which, while comparatively light, is yet firm, strong, and durable, and impenetrable to moisture, thus securing the preservation of the wood or other material of which the coffin or burial-case inserted in the "tomb" is made, from decay or rot, as is obvious.

The expense of handling and transporting the receptacle when made in two pieces only, would forbid its use.

I disclaim the coffin-vault or receptacle of cement composed of two pieces, and present a modified

Claim.

I claim as the invention of the said RALPH HUNT—

A coffin-vault or receptacle, made of cement and in sections or parts of small size, for convenience of transportation, said parts being suitably grooved for being joined with cement, all as and for the purpose described

DANIEL M. SPROGLE.
